(57) **CLAIM**

The ornamental design for outerwear as shown and described.

DESCRIPTION

FIG. 1 is a right side front perspective view of outerwear showing my new design in a first state;

FIG. 2 is a right side view thereof;

FIG. 3 is a right side rear perspective view thereof;

FIG. 4 right side front perspective view of outerwear showing my new design in a second state;

FIG. 5 is a right side view thereof; and,

FIG. 6 is a right side rear perspective view thereof.

The broken lines depicting the remainder of the outerwear form no part of the claimed design.
